UNITED STATES PATENT OFFICE.

LUCIEN F. BRUCE, OF SPRINGFIELD, MASSACHUSETTS.

CARTRIDGE-FEEDER FOR MACHINE-GUNS.

SPECIFICATION forming part of Letters Patent No. 247,158, dated September 20, 1881.

Application filed July 23, 1881. (No model.)

To all whom it may concern:

Be it known that I, LUCIEN F. BRUCE, a citizen of the United States, residing at Springfield, in the county of Hampden and State of Massachusetts, have invented new and useful Improvements in Cartridge-Feeders for Machine-Guns, of which the following is a specification.

This invention relates to the details of the construction of cartridge-feeding devices for machine and other guns, the object being to provide an improved feeder for said purpose adapted to receive cartridges rapidly and conveniently from an ordinary paper packing-box, thus obviating the necessity of providing a special packing-box for cartridges destined to be fed therefrom to said guns, and, having received the cartridges from said box in two lines, to automatically operate to cause said cartridges to be delivered to and through the hopper of said gun in a single line formed alternately of one and then the other of said two lines of cartridges; and, furthermore, to provide for said feeding devices improved cartridge straightening, guiding, and feed-stopping mechanism.

In the drawings forming part of this specification, Figure 1 is a perspective view illustrating my improved cartridge-feeder applied to a machine-gun, and showing the part of said gun to which the feeder is applied. Fig. 2 is a view, partly in section, showing a portion of said gun and parts of the lower end of said feeder. Fig. 3 is a rear elevation of the cartridge-conductor of the feeder, showing that part above its foot. Fig. 4 is a view, partly in section, of some of the detail parts. Fig. 5 is a perspective view, partly in section, of the cartridge-feeder filled with cartridges. Fig. 6 is a perspective view of the front side of the parts shown in Fig. 3, showing one of the grooves of the conductor emptied of its cartridges. Fig. 7 illustrates the position in which a box of cartridges is held when placing them in the conductor of the feeder. Fig. 8 is a transverse section through the conductor between the cartridges. Fig. 9 is a plan view of a box of cartridges with the cover removed. Fig. 10 illustrates the part *h* and the hopper *d* of the gun, having some of my improve-

ments applied thereto independent of my particular cartridge-conductors.

In the drawings, *h* represents that part of a machine-gun upon which the hopper *d* is located, and to which the cartridge-feeder is secured.

x is the carrier-wheel of the gun. *c* is the foot of the feeder.

*e*² is an arm, hanging down over the end of the foot *c*.

e is a screw passing through arm *e*², and having a shoe, *e'*, hung on its end under arm *e*².

d is an upwardly-projecting end to the hopper of the gun, onto which the foot of the feeder is secured by screw *e* and shoe *e'*.

i are vertical supports on the side of the foot *c* of the feeder. *o* is a roller-stop sliding vertically between supports *i*.

o' is a spring-actuated bolt in the roller-stop *o*.

n is a longitudinally-fluted cartridge-straightening roller, supported on proper bearings between supports *i* on the side of the foot *c*, and one side of which projects through the side of said foot and into the passage therein, through which the cartridges pass on their way to the carrier-wheel *x* of the gun.

b is the single-grooved portion of the cartridge-conductor, from which rises vertically a flat post, *a'*. A recess is formed on the rear face of said parts *b* and *a'*, as in Fig. 3, for the reception of the spring 2 and piston 3, the upper end of said piston having a bearing on the under side of a stud, 4, projecting from the rear face of the cartridge-conductor *a*, and a collar 85 just below the upper end of said piston bears upon the upper end of spring 2.

6 is a screw passing through the post *a'* into the back of the cartridge-conductor *a*, and upon which the latter swings.

z are two switch-plates, having their upper edges inclined toward the single groove in the part *b* of the cartridge-conductor, and setting thereon on each side of said groove.

7 are slots in the lower ends of the sides 95 of the cartridge-conductor *a*. *f* is the central partition between the two grooves in said conductor *a'*.

8 is the cartridge-box.

v is a curved guide-lip hanging on the lower 100

end of the cartridge-feeder opposite to the side of roller n .

The single-grooved part b of the feeder, together with the flat post a' and the foot c , constitute a frame, which, as well as the grooved conductor a and the other parts named, are of a suitable metallic construction.

The part h of the gun and the carrier-wheel x thereof represent parts of the well-known 10 Gatling gun.

The form and general construction of the feeder can well be understood by reference to Figs. 1 and 5, and its operation is as follows: The feeder is placed in the hopper of the gun 15 and fastened thereon by turning screw e and forcibly clamping the end d of the hopper between the face of shoe e' and the end of the foot c , and in so doing the parts of the feeder are brought into the relation to the parts of 20 the gun-hopper which is illustrated in Figs. 1 and 2. The conductor a is now charged with cartridges, the operator taking the box 8 in one hand, holding the other against the heads of the cartridges to retain them in the box, 25 and introducing the end of the series of cartridges in the box into the two grooves in the conductor a , as in Fig. 7, he draws the box down until the heads of all the cartridges have entered said grooves, when he draws the box 30 away from them, leaving them as seen in Fig. 5, one column leading directly down into the hopper of the gun, and the other resting upon the inclined edge of one of plates z by the side of the lower single groove. As before mentioned, 35 said conductor a is especially adapted to take cartridges from an ordinary paper packing-box, provision for this having been made by making the partition f between the two grooves in the conductor a of a wedge form in 40 cross-section, thus preventing the spreading effect of a thick partition passing between the cartridges at some distance below their heads, which would be to crowd them apart laterally and break the cartridge-box; and when it is 45 remembered that to feed the Gatling gun when being fired the operator must place the contents of each cartridge-box in the conductor with the utmost rapidity, the great utility of the described form of partition f will be appreciated. As the cartridges feed down to the hopper of the gun those in the groove of conductor 50 a , which is in a line with the groove in the part b below, as in Fig. 5, feed down first, and those in the adjoining groove remain stationary; 55 but as soon as the last cartridge in said down-moving row has passed from the groove in the conductor a into the single groove in the part b the weight of the adjoining column of cartridges upon the inclined edge of whichever 60 of the switch-plates z it may rest upon causes the lower end of the conductor a to swing away from said switch-plate and carry the end of the groove in which said stationary row of cartridges is over the end of the single groove in 65 the part b , and so leave said cartridges free to

follow the first-named column into the hopper of the gun.

Thus it will be seen that during the down-feeding of the cartridges in conductor a , cartridges being in both grooves, whenever the 70 groove therein which is in a line with the single groove below becomes empty the lower end of said conductor will swing and bring the adjoining groove into line with the upper end of said single groove. When the lower 75 end of said conductor a swings from one side to the other, as above described, the spring 2 , Fig. 3, is slightly compressed as said conductor swings past the center, and, then springing back against the shoulder on piston 3 , throws 80 the lower end of said conductor quickly to the side toward which it was started by the weight of one of the columns of cartridges against the edge of plate z , as aforesaid.

When the cartridges have been placed in 85 the grooves in the conductor a their outer ends, owing to the weight of the ball, hang down, as in Fig. 5, and they maintain that position on reaching the foot c of the feeder; but after they arrive at that point it is desirable that 90 they should assume such a position as will cause them to strike squarely against the carrier x of the gun when they reach it, and not fall ball first against it.

To so control the movement of the cartridges 95 to straighten them and change the position of those at the lower end of the column, so that those numbered 10 and 11 in Fig. 5 shall take the position of that one numbered 12 before it reaches said carrier x , the fluted straightening- 100 roller n is hung in the side of the foot c , so as to revolve partly in the cartridge-passage there-through, and is supported between supports i i , as above described. Said cartridges, on reaching roller n , lie on one of the flutes there-on, and their weight revolves said roller, and the cartridges from thence drop against the side of lip v , and are made to fall in proper position onto the carrier x of the gun, as shown 105 in Fig. 2.

The sliding roller-stop o is fitted to be moved up and down between the supports i i , and is held frictionally in place, up or down, by the pressure of the end of the piston o' against one of said supports, actuated by a suitable 110 spring.

When it becomes desirable from any cause to stop the cartridges from feeding down through the foot c to the carrier x , said roller-stop o is moved down against the roller n , 115 thereby preventing it from revolving and stopping the cartridges from passing by it.

The advantages pertaining to the employment of the straightening-roller n and the curved lip v in the hopper of a machine-gun 120 may be enjoyed by so constructing said hopper that said roller will operate in the side thereof, as it does in the side of the foot c of the feeder, and the curved lip v may be extended down toward the carrier x from one side of 125

the hopper and be made a part thereof. Thus any ordinary cartridge-feeder may be secured to the gun to deliver cartridges to a hopper provided with said roller and curved lip, as 5 illustrated in Fig. 10.

What I claim as my invention is—

1. In a cartridge-feeder for guns, the combination, with the single-grooved cartridge-conductor *b*, of the vibrating double-grooved cartridge-conductor *a*, pivoted to an upright support on said single-grooved conductor, and the switch-plates *z z*, substantially as set forth.
2. The cartridge-conductor *a*, provided with two parallel flanged grooves, the partition between said grooves being wedge-shaped on its front part, substantially as and for the purpose set forth.
3. In combination with the single-grooved cartridge-conductor *b* and with the foot *c*, the fluted straightening-roller *n*, hung to revolve

in the side of said foot *c*, substantially as set forth.

4. The cartridge-conductor *b*, and the fluted straightening-roller arranged at the side of said conductor and projecting into the foot *c*, 25 the curved lip *v*, at the bottom of the conductor, in combination with the carrier-wheel *x*, the fluted roller, the lip, and carrier-wheel, arranged relatively to each other substantially as shown, so as to hold the cartridge in proper 30 position between them until it is carried forward into the gun.

5. In combination, the single-grooved conductor *b*, the vibrating double-grooved conductor *a*, spring 2, and piston 3, substantially 35 as and for the purpose set forth.

LUCIEN F. BRUCE.
